UNITED STATES PATENT OFFICE

CARL EURIT, OF TULSA, OKLAHOMA

STRAIGHT LIFT BEAM HANGER FOR OIL WELL PUMPING RIGS

Application filed June 24, 1932. Serial No. 619,150.

This invention relates to certain new and useful improvements in straight lift beam hanger for oil well pumping rigs.

The primary object of the invention is to provide a straight lift beam hanger for oil pumping rigs wherein a frame structure comprised of pivotally connected link members assembled in trapezium formation is interposed between the pumping end of a walking beam and the upper end of a polish rod to eliminate the bisector described by the pumping end of the walking beam during oscillatory motion thereof to cause the polish rod vertically to reciprocate or to be lifted and lowered in a manner for eliminating side wear on the polish rod and gland or stuffing box through which the rod moves that would otherwise be caused by the arc described by the pumping end of the walking beam.

A further object of the invention is to provide a straight lift beam hanger for oil well pumping rigs of the foregoing character wherein the link frame construction is pivotally supported upon the pumping end of a walking beam while the clamp member that is engaged with the upper end of the polish rod is shiftably and pivotally supported upon the lower link member of the link frame permitting relatively free movement between the links forming the frame of trapezium form whereby the polish rod is raised and lowered in a true vertical line and side movement thereof resulting in wear on the stuffing box and crystallization of the polish rod is eliminated.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a side elevational view of a walking beam construction for oil well pumping rigs showing the counter-balance operating wheel for the walking beam and a link frame construction of trapezium form interposed between the pumping end of the

walking beam and the upper end of the polish rod, and illustrating by dotted lines positions assumed by the link frame during movements of the walking beam;

Figure 2 is a fragmentary side elevational view of the lower link member of the link frame showing the rack support for the polish rod clamp; and

Figure 3 is a top plan view of the lower link member of the link frame.

Referring more in detail to the accompanying drawing, the reference numeral 5 designates a standard that pivotally supports at its upper end as at 6, a walking beam 7 having the end 8 thereof engaged with operating devices therefor and its pumping end 9 connected to the polish rod 10.

The operating means for the walking beam 7 includes a counter-balanced drive wheel 11 mounted upon a supporting frame 12 driven in any appropriate manner with a link rod connection 13 between the wheel 11 and end 8 of the walking beam.

During operation of the walking beam 7, the end 9 thereof describes an arc and to compensate for the changes in position of the pumping end 9 of the walking beam relative to the polish rod 10 and to permit the latter to be raised and lowered in the absence of side movement, a link frame structure is interposed between the pumping end of the walking beam and the upper end of the polish rod. The link frame structure is of trapezium form and includes an upper link 14 comprising a pair of side bars 15 with a hanger block 16 interposed therebetween and pivotally supported as at 17 upon the pumping end 9 of the walking beam. The lower link member 18 of the link frame structure comprises a pair of spaced parallel side bars 19 of greater length than the side bars 15 of the upper link member, the side bars 19 being connected together by a pair of spaced angle brackets 20 as shown in Figure 3. The ends of the link members 14 and 18 are connected by the vertical link rods 21 and 22 by means of pivot pins 23 extending between the side bars of the link members 14 and 18, the link rod 22 being of a length greater than the length of the link rod 21 so that the link

60

100

frame structure is of trapezium form as illustrated in Figure 1.

The block 16 that supports the link frame structure upon the pumping end 9 of the 5 walking beam 7 is disposed nearer the link rod 21 than the link rod 22 and the support for the upper end of the polish rod 10 is mounted upon the lower link member 18 adjacent the link rod 21. The support for the 10 polish rod includes a block 24 secured as at 25 to the upper edge of each side bar 19, being transversely aligned and located between the angle brackets 20, the upper face of each block 24 having spaced sockets 26 therein as 15 illustrated with the sockets of the spaced blocks transversely aligned. The polish rod 10 is engaged at its upper end by a clamp 27 that carries diametrically opposite bearing pins 28 that are selectively received in the 20 transversely aligned sockets 26 as shown in Figures 2 and 3.

From the above detailed description of the invention, it is believed that the construction and operation thereof will at once be apparent, it being noted that during pivotal movement of the walking beam 7, the link frame structure of trapezium form assumes the positions illustrated by dotted lines in Figure 1 to compensate for the arc described 25 by the pumping end 9 of the walking beam so that the polish rod 10 moves up and down in a true vertical line with all side movements thereof eliminated. With the polish rod directly engaged with the pumping end 30 of the walking beam as heretofore practiced, there is considerable side movement imparted to the polish rod in addition to the up and down movement thereof which results in binding engagement between the polish rod 35 and stuffing box through which the same slides, this action soon resulting in crystallization of the rod and breakage thereby causing inconvenience and expense as well as loss of time in repair and replacement work. 40 With the present apparatus embodying the link frame structure pivotally carried by the pumping end of the walking beam and with which the upper end of the polish rod 10 is engaged, all side movement of the polish 45 rod is eliminated and wear on the polish rod in the normal operation thereof is thereby reduced to a minimum.

While there is herein shown and described the preferred embodiment of the invention, it 55 is nevertheless to be understood that minor changes may be made therein without departing from the spirit and scope of the invention as claimed.

I claim:—

60 1. In a straight lift beam hanger for oil well pumping rigs, in combination, the pumping end of a walking beam, the upper end of a polish rod and a link frame structure interposed between the walking beam and 65 polish rod and being of trapezium form, the

link frame structure including upper and lower link members formed of spaced bars, a pivot block for the walking beam between the bars of the upper link member and notched blocks on the bars of the lower link member for the pivotal support of a polish rod clamp. 70

2. In a straight lift beam hanger for oil well pumping rigs, in combination, the pumping end of a walking beam, the upper end of a polish rod and a link frame structure interposed between the walking beam and polish rod and being of trapezium form, and pivotally connected to the beam and rod, the link frame structure including upper and lower link members formed of spaced bars, a pivot block for the walking beam between the bars of the upper link member and notched blocks on the bars of the lower link member for the pivotal support of a polish rod clamp. 75

3. In a straight lift beam hanger for oil well pumping rigs, in combination, the pumping end of a walking beam, the upper end of a polish rod and a link frame structure interposed between the walking beam and polish rod and being of trapezium form, the link frame structure including upper and lower link members of unequal lengths formed of spaced bars, a pivot block for the walking beam between the bars of the upper link member and notched blocks on the bars of the lower link member for the pivotal support of a polish rod clamp. 80

4. In a straight lift beam hanger for oil well pumping rigs, in combination, the pumping end of a walking beam, the upper end of a polish rod and a link frame structure interposed between the walking beam and polish rod and being of trapezium form, and pivotally connected to the beam and rod, the link frame structure including upper and lower link members of unequal lengths formed of spaced bars, a pivot block for the walking beam between the bars of the upper link member and notched blocks on the bars of the lower link member for the pivotal support of a polish rod clamp. 85

5. In a straight lift beam hanger for oil well pumping rigs, in combination, the pumping end of a walking beam, the upper end of a polish rod and a link frame structure interposed between the walking beam and polish rod and being of trapezium form, the link frame structure including upper and lower link members of unequal lengths formed of spaced bars, a pivot block for the walking beam between the bars of the upper link member and notched blocks on the bars of the lower link member for the pivotal support of a polish rod clamp. 90

6. In a straight lift beam hanger for oil well pumping rigs, in combination, the pumping end of a walking beam, the upper end of a polish rod and a link frame structure interposed between the walking beam and polish rod and being of trapezium form, and pivotally connected to the beam and rod, the link frame structure including upper and lower link members of unequal lengths formed of spaced bars, a pivot block for the walking beam between the bars of the upper link member and notched blocks on the bars of the lower link member for the pivotal support of a polish rod clamp. 95

7. In a straight lift beam hanger for oil well pumping rigs, in combination, the pumping end of a walking beam, the upper end of a polish rod and a link frame structure interposed between the walking beam and polish rod and being of trapezium form, the link frame structure including upper and lower link members of unequal lengths formed of spaced bars, a pivot block for the walking beam between the bars of the upper link member and notched blocks on the bars of the lower link member for the pivotal support of a polish rod clamp. 100

8. In a straight lift beam hanger for oil well pumping rigs, in combination, the pumping end of a walking beam, the upper end of a polish rod and a link frame structure interposed between the walking beam and polish rod and being of trapezium form, the link frame structure including upper and lower link members formed of spaced bars, a pivot block for the walking beam between the bars of the upper link member and notched blocks on the bars of the lower link member for the pivotal support of a polish rod clamp. 105

9. In a straight lift beam hanger for oil well pumping rigs, in combination, the pumping end of a walking beam, the upper end of a polish rod and a link frame structure interposed between the walking beam and polish rod and being of trapezium form, the link frame structure including upper and lower link members formed of spaced bars, a pivot block for the walking beam between the bars of the upper link member and notched blocks on the bars of the lower link member for the pivotal support of a polish rod clamp. 110

10. In a straight lift beam hanger for oil well pumping rigs, in combination, the pumping end of a walking beam, the upper end of a polish rod and a link frame structure interposed between the walking beam and polish rod and being of trapezium form, and end links connecting the upper and lower link members being of unequal lengths to produce the trapezium form for the link frame structure. 115

11. In a straight lift beam hanger for oil

- well pumping rigs, in combination, the pumping end of a walking beam, the upper end of a polish rod and a link frame structure interposed between the walking beam and 5 polish rod and being of trapezium form, and pivotally connected to the beam and rod, the link frame structure including upper and lower link members formed of spaced bars, a pivot block for the walking beam between the 10 bars of the upper link member and notched blocks on the bars of the lower link member for the pivotal support of a polish rod clamp, and end links connecting the upper and lower link members being of unequal lengths to 15 produce the trapezium form for the link frame structure.
7. In a straight lift beam hanger for oil well pumping rigs, in combination, the pumping end of a walking beam, the upper 20 end of a polish rod and a link frame structure interposed between the walking beam and polish rod and being of trapezium form, the link frame structure including upper and lower link members of unequal lengths 25 formed of spaced bars, a pivot block for the walking beam between the bars of the upper link member and notched blocks on the bars of the lower link member for the pivotal support of a polish rod clamp, and end links 30 connecting the upper and lower link members being of unequal lengths to produce the trapezium form for the link frame structure.
8. In a straight lift beam hanger for oil well pumping rigs, in combination, the 35 pumping end of a walking beam, the upper end of a polish rod and a link frame structure interposed between the walking beam and polish rod and being of trapezium form, and pivotally connected to the beam and rod, 40 the link frame structure including upper and lower link members of unequal lengths formed of spaced bars, a pivot block for the walking beam between the bars of the upper link member and notched blocks on the bars 45 of the lower link member for the pivotal support of a polish rod clamp, and end links connecting the upper and lower link members being of unequal lengths to produce a trapezium form for the link frame structure.
- 50 9. In a straight lift beam hanger for oil well pumping rigs, in combination, the pumping end of a walking beam, the upper end of a polish rod and a link frame structure interposed between the walking beam and polish rod and being of trapezium form, the link frame structure including upper and lower link members of unequal lengths formed of spaced bars, a pivot block for the walking beam between the bars of the upper 55 link member and notched blocks on the bars of the lower link member for the pivotal support of a polish rod clamp, and end links connecting the upper and lower link members being of unequal lengths to produce the trapezium 60 form for the link frame structure, and said 65 pivot and notched blocks being located nearer the shorter end link than the longer end link.
10. In a straight lift beam hanger for oil well pumping rigs, in combination, the 70 pumping end of a walking beam, the upper end of a polish rod and a link frame structure interposed between the walking beam and polish rod and being of trapezium form, and pivotally connected to the beam and rod, 75 the link frame structure including upper and lower link members of unequal lengths formed of spaced bars, a pivot block for the walking beam between the bars of the upper link member and notched blocks on the bars 80 of the lower link member for the pivotal support of a polish rod clamp, end links connecting the upper and lower link members being of unequal lengths to produce the trapezium form for the link frame structure, and 85 said pivot and notched blocks being located nearer the shorter end link than the longer end link.
- In testimony whereof I affix my signature.
